ELECTRICAL WATER HEATER

Application filed March 19, 1928. Serial No. 262,722.

The invention relates to devices for heating water by electrical heating means, which make use of the eddy currents or hysteresis set up in a substantially solid bar of magnetic material.

5 A further object is to provide means whereby the heat generated in the bar may be most efficiently transmitted to the medium to be heated.

10 Another object of the invention is to produce a heater which is easily installed, requires no attention after installation, is practically indestructible, and cannot be accidentally prevented from functioning. The 15 forms of the invention shown in the accompanying drawing are preferred, although it will be understood that various modifications within the scope of the appended claims may be made without departing from the spirit of 20 the invention set forth therein. These objects are attained by the arrangements shown in the accompanying drawing and described in detail in the specification.

25 Referring more particularly to the drawings, in which

Fig. 1 shows a vertical plan view partly in section on the line 1—1 of Fig. 2 of the application of the invention to the usual form of household hot water container;

30 Fig. 2 shows a top plan view of the arrangement shown in Fig. 1 partly in section on the line 2—2 of Fig. 1; and

Fig. 3 shows the modification of the application of the invention.

35 Similar reference numerals indicate similar parts throughout the several views, and in the drawings, reference numerals 1 indicate a substantially solid U-shaped bar forming portions of the closed magnetic circuit of a 40 transformer-like structure. Numeral 2 indicates a plurality of passageways formed in the bar, through which passageways the fluid to be heated may circulate and absorb the heat transferred from the bar 1 in a quick and

45 thorough manner. Numeral 3 indicates the wall of the fluid container 10 to which the invention is applied. The bar 1 is provided with extensions 4 projecting through the wall of the container for the purpose of providing 50 means of attachment for a U-shaped bar 5 of

laminated structure of magnetic material which completes the closed magnetic circuit of the transformer-like heater. Bars 1 and 5 are welded at their junction point to insure perfect contact and to obviate current loss by 55 resistance at the joint. A coil of electrical conducting wire 6 is wound about the laminated bar 5 and suitable connections are made to the usual alternating current lighting circuit. 60

The bar 1 is of substantially solid construction to provide a maximum hysteresis loss and to set up eddy currents at all possible points, which loss and currents are transformed into heat. The passageways 2 provide for exposure of a larger surface and permit circulation of the fluid to be heated, thereby securing the most efficient transfer of heat. 65

Laminated construction of the bar 5, according to the usual practice in transformers, 70 eliminates loss of current by resistance to the induced current in the bar, which resistance would be a loss, since only a small portion of the heat developed thereby would be conducted to the bar 1 and transmitted to the fluid. 75

A thermostat 7 of any known construction is placed in the circuit, the thermo-sensitive element projecting into the fluid container, as clearly indicated in Fig. 1. A casing 8 covers and encloses all of the heater structure not 80 enclosed within the fluid container 10. In the construction shown in Fig. 1, an additional space 9 is provided between the body of the bar 1 and the wall 3 of the fluid container for the purpose of permitting better circulation 85 of the medium to be heated. The space 9 between the bar 1 and walls 3 of the fluid container is eliminated in Fig. 3 to permit making the bar 1 integral with the container 10. The usual cold water pipe 11 leading to the 90 bottom of the container 10 and a hot water pipe 12 leading off from the top of the container 10 are shown.

From the construction described, it will be apparent that we have provided a simple, efficient type of fluid heater whereby the heating effects of the eddy currents or hysteresis produced in the transformer-like structure may be most efficiently used for heating a fluid circulating medium. 95 100

Having described our invention, what we claim as new and desire to secure by Letters Patent of the United States is:

A water heater comprising a transformer of laminated construction, a heating element being substantially solid and having a plurality of longitudinal bores extending therethrough and opening at both ends of said element, arms carried by the transformer and complementary arms carried by the heating element for spacing said element from said transformer, said arms being adapted to extend through the side wall of a boiler for securing the heating element within the boiler.

15 In testimony whereof we affix our signatures.

ERNEST E. KITTREDGE.
